UNITED STATES PATENT OFFICE

RUDOLPH F. STEHLIK, OF CHICAGO, ILLINOIS, ASSIGNOR TO RESERVE HOLDING COMPANY, OF CHICAGO, ILLINOIS, A CORPORATION OF DELAWARE

MULTIOFFICE TELEPHONE SYSTEM

Original application filed March 14, 1927, Serial No. 175,187. Divided and this application filed December 31, 1928, Serial No. 329,490. Renewed July 14, 1930.

This invention relates in general to multi-office telephone systems but more particularly to such systems as comprise in one network offices or exchanges of two different kinds, the offices of one kind being manual offices wherein connections are completed by means of automatic switches, and the object of the invention is to provide new and improved circuit arrangements for handling interoffice calls between the automatic and manual exchanges.

Systems having both kinds of exchanges as above pointed out are becoming quite common and may arise either by consolidation of existing manual and automatic systems, serving the same territory, or by the process of changing over a manual system to an automatic system. Usually in the latter case only one office at a time is converted from manual to automatic and it follows that during the period of transition there will necessarily be both kinds of offices in operation. However the above situation may arise, it is necessary to provide suitable circuit arrangements for handling calls from the manual offices to the automatic offices, and from the automatic offices to the manual offices. The present invention is concerned only with the latter class of calls, and provides certain improvements in systems comprising automatic to manual trunks which are accessible to selector switches in the automatic offices and terminate in plugs in front of a B operator at the manual office, together with call registers for registering the digits in telephone numbers called by automatic subscribers when the trunks are taken for use, and an indicating device upon which such numbers are shown to the operator one after the other as fast as she can complete the desired connections.

This application is a division of my pending application Serial No. 175,187, filed March 14, 1927, on which United States Patent No. 1,775,834 was granted Sept. 16, 1930.

The main feature of the invention in this divisional application relates to the special method of multiplying switches at an intermediate distributing frame.

In the drawings, comprising Figs. 1, 2, 3,

and 4, there is shown by means of the usual circuit diagrams the apparatus and circuit connections thereof which is involved in a complete connection extending from the automatic substation A, Fig. 1, to a manual substation A', Fig. 2.

The apparatus indicated in Fig. 1, is located in an automatic exchange, while the apparatus indicated in Figs. 2, 3, and 4, is located in a manual exchange. Inasmuch as the automatic switching equipment itself and the manual equipment are both well known and of the usual type, no detailed description of the mechanical features of this apparatus will be given, except insofar as it is found convenient or necessary to do so in the explanation of the operations of the circuits.

Referring to Fig. 1, the substation A is one of a plurality of ordinary automatic substations terminating in the automatic exchange previously referred to, and is provided with the usual talking equipment and ringer, and also with a calling device of a well known type which is indicated by the reference character S, through the medium of which the subscriber controls the central office switches.

The line conductors 11 and 12 extend to the exchange where they terminate in the line switch C, which may be briefly described as a rotary line switch whose moveable terminals or wipers have no normal position, and which have movements in a forward direction only. The construction of a line switch of this type is well known in the art, and its function, also well understood, is to extend its associated line when calling to an idle trunk line. In carrying out this object, a plurality of these individual line switches are given access to a group of trunk lines extending to first selector switches. One of the trunk lines to which the line switch C has access is shown in the drawings as extending to the first selector D, which is a vertical and rotary selector of the well known Strowger type.

In a multi-office system of the kind herein contemplated the first selector switches are usually known as office selectors and the selector D in common with a plurality of similar selectors has access to a plurality

has access to the register set shown in the drawings and also to the other register sets which are provided at the B operator's position in which the cord circuit O terminates. The line switch C' is of well known construction and function and on this account will not be described in detail as to its mechanical operation. The banks of the line switch C' are what is known as 25 point banks. The 10 banks of the register selectors at the position are connected in multiple and a cable connects the multiply connected and a cable one side of the intermediate banks with frame, indicated I. D. F., Fig. 4, from which point they are jupered to the various register sets in different multiple combinations as will be more fully explained hereinafter.

Referring again to Fig. 2, there is shown in the lower right hand corner, a trunk circuit TC, which extends to an information and complaint operator's position. When an incomplete telephone number is displayed, the B operator will plug into the trunk circuit TC, thereby connecting the calling party to the information and complaint operator. The latter operator either completes the call or advises the calling party of his error. Relay ATB, in Fig. 2, is what is known as a busy relay. This relay is connected at this particular B

The latter operator either connects the information or advises the calling party of his error. Relay ATB, in Fig. 2, is what is known as the all trunk busy relay. This relay is common to the register sets at this particular operator's position, and when operated, artificially renders all the trunks extending from the automatic exchange to the B operator's position busy. TK in Fig. 2, there is shown one of a series of keys by means of which

operator's position artificially renders all the trunks from the automatic exchange to the operator's position busy.

At TK in Fig. 2, there is shown one of a plurality of similar keys by means of which the B operator may busy the trunks coming into her position in groups of eight.

In the dotted rectangle marked POS. 35 is shown an operator's position. The operator at position

40 Fig. 2, there is shown an operator's position linking key for the B operator at position 3; at POS. 2 there is shown the position linking key for the B operator at position 45 which position is the position at position 2, circuit O is located, and at POS. 1 there is shown in the dotted rectangle the position linking key for the B operator at position 1. The position linking keys are for the purpose of permitting an operator at an intermediate position to link or connect her head set to the cord circuits of positions on either side of her position.

upper left hand corner of Fig. 2 MB the bus-bar to

55 In the upper left hand corner of Fig. 2, there is illustrated at MB the bus-bar to which the main battery is directly connected. The conductor 273 illustrates the means by which the main battery is connected to the lower bus-bar and the conductor 274 illustrates the means by which all the apparatus at the operator's position is connected to main battery, it being understood that all the battery symbols shown separately in the drawings are in reality connected to conductor 274.

60 In the upper part of Fig. 3, there is shown

65

the set-up pilot lamps SUP by means of which the B operator is enabled to know which register sets are in use.
In the lower part of Fig. 3, there is shown by means of the usual circuit diagrams the 70 method of connecting up the first seven register sets so that they may be normally available for use, while the eighth or reserve register set is normally made busy. When all the first seven register sets are busy, the 75 eighth register set is then rendered available for use to take care of any call which may have come in after the seventh or last register set was seized and before all of the trunks were made busy.
Having described in a general way the lay-out herein disclosed, the operator will now be described who is pur-

Having described in a general way the layout of the system herein disclosed, the operation of the system will now be described more in detail, it being assumed for this purpose that the subscriber at substation A, Fig. 85, desires to obtain a connection with the manual subscriber at substation A' Fig. 2, whose telephone numbers, it will be assumed, is 23456. When the receiver is removed at substation A, a circuit is completed over the line conductors 11 and 12 for the line relay 14 of the individual line switch C. Upon energizing, line relay 14 completes at its armature 20 a circuit which extends to the switching relay 13 and stepping magnet 15 in series to battery, and at its armature 19 connects the test wiper 26 to the above circuit at a point midway between the switching relay and the stepping magnet. The operation now depends upon whether the first selector trunk upon which the wipers of the line switch are in connection is busy or is not busy. If the trunk line is busy, the t contact 31 associated therewith will have ground potential upon it, the switching relay 13 will be short circuited, and the stepping magnet 15, which interrupts its own circuiters 25-27, inclusive, step-by-step in search of an idle trunk line. This operation will continue as long as the test wiper 26 continues to engage grounded or busy test contacts. However, we may assume that in the case when a call is initiated the select idle, and the test contact 31 therefore grounded. Under these circumstances the line relay 14 is energized the switch relay 13 is energized immediately, with the result that the line conductors 11 and 12 are disconnected from the winding of the line relay 14 and from the armatures 16 and 18 and their wipers 25 and 27, bank contacts 32, and armatures 60 and 62 and their contacts, to the upper and lower contacts of the line relay 50 of the selector D as above described, the line relay 50 will be energized and will

As soon as the collector D as above described, 50 will be energized and will

1,815,169

on energizing, the latter relay prepares the circuit of the selector for operation in its vertical movement in the usual manner, and also completes a holding circuit extending, back to the line switch C as follows: ground, working contact of armature 63 and said armature, conductor 64, bank contact 31, test wiper 26, armature 17 and its working contact, winding of the switching magnet 15, and the winding of the stepping magnet 15 to the battery. It is understood that the above holding circuit is completed before the slow acting relay 14 has had time to deenergize. In addition to maintaining the switching relay energized, the holding circuit also serves to provide ground to the multiple test contacts in which the private lines of the conductors 28 terminates in the banks of the connectors which have access to the line of sub-station A, thereby guarding the connection against intrusion in the customary manner. The calling subscriber may now operate the calling device S in accordance with the digit of the desired number.

Two interlockers 64, produced in the circuit of the line relay 50, and the said relay is accordingly twice deenergized, momentarily, transmitting at each deenergization an impulse of current through the slow-acting series relay 52 and the vertical magnet 56 to battery. By the operation of a switch hereinafter described, the selector shunt is connected to the line conductors.

53 will be energized over a circuit which extends by way of the test wiper 71, armature springs 61 and its resting contact, off normal springs 59, interrupter contact of the rotary magnet, and the winding of stepping relay 53 to battery. The circuit of the stepping relay will therefore again close the circuit to rotate the rotary magnet wipers into engagement with the next set of bank contacts. This operation will continue as long as the test wiper 71 continues to ping relay and the rotary magnet are alternately energized and deenergized will engage grounded or busy test contacts. In the present case, it will be assumed that the first idle trunk line, and when therefore the test wiper arrives at test contact 74 and the rotary magnet is deenergized, the stepping relay 53 will not again be operated, but instead the switching relay 55, which heretofore has been short circuited, will be energized by current flowing over the following path: grounded contact 31 and also to the multiple test contacts in which the private lines of the conductors 28 terminates in the banks of the connectors which have access to the line of sub-station A, thereby guarding the connection against intrusion in the customary manner. The calling subscriber may now operate the calling device S in accordance with the digit of the desired number.

Two interlockers 64, produced in the circuit of the line relay 50, and the said relay is accordingly twice deenergized, momentarily, transmitting at each deenergization an impulse of current through the slow-acting series relay 52 and the vertical magnet 56 to battery. By the operation of a switch hereinafter described, the selector shunt is connected to the line conductors.

the following path: grounded contact 64, winding of the switching relay 55, off normal springs 59, interrupter contacts of the rotary magnet 54, and the winding of the stepping relay 53 to battery. Owing to the high resistance of the switching relay 55, the stepping relay 53 is not operated. Upon energizing, relay 55 disconnects the incoming line conductors from the winding of the line relay 50 and extends them by way of armatures 60 and 62 and their working contacts, wipers 70 and 72, bank contacts 73 and 75, trunk conductors 76 and 78, and normally closed contacts of the reversing relay 100, to the upper and lower windings of the line relay 101 of the repeater E.

When the line is extended to the repeater as above explained, the line relay 101 is energized and closes a circuit for the slow acting release relay 102. Upon energizing, relay 102 completes a holding circuit extending back to the selector D and the line switch C as follows: ground, armature 112 and its working contact, conductor 77, test contact 74, test wiper 71, and the armature 61 and its working contact to conductor 64, where it joins the previously described holding circuit extending back to line switch C. The above described circuit serves to maintain relays 55 and 13 energized throughout the duration of the connection.

In addition to closing the circuit of the stepping relay 53 for the automatic circuit of the selector D, the stepping relay 53 also acts in the level opposite which they are located. The stepping relay 53 accordingly energizes the locking circuit for the stepping relay 53, which circuit of the stepping relay 53 is connected to the line switch C.

In addition to closing the holding circuit for the automatic switches C and D, the relay 102 of the repeater E prepares a circuit at its 102 armature 115 for the slow acting relay 103; closes a circuit at its armature 114 for energizing relay 104; and at its armature 113 completes a circuit for energizing the line relay 125 206 of the cord circuit O, Fig. 2 over the following path: from ground by way of the normally closed springs controlled by armature 118, working contact of armature 113 and magnet 54 also for the stepping circuit for the stepping magnet 54 also which accordingly deenergizes and energizes the rotary magnet, which leenergizes also, and again closes the connection. In addition to closing the holding circuit for the automatic switches C and D, the relay 102 of the repeater E prepares a circuit at its 102 armature 115 for the slow acting relay 103; closes a circuit at its armature 114 for energizing relay 104; and at its armature 113 completes a circuit for energizing the line relay 125 206 of the cord circuit O, Fig. 2 over the following path: from ground by way of the normally closed springs controlled by armature 118, working contact of armature 113 and magnet 54 also for the stepping circuit for the stepping magnet 54 also which accordingly deenergizes and energizes the rotary magnet, which leenergizes also, and again closes the connection.

and its resting contact, upper left hand winding of the repeating coil of the cord circuit O, normally closed springs controlled by armature 237, and upper winding of the line relay 206 to battery. Upon energizing, line relay 206 causes the energization of the release relay 205. The latter relay upon energizing connects ground at armature 235 to the lower winding of the line relay 206 so that the line relay may be maintained energized by a bridge at the repeater E.

Referring now to the repeater E, the relay 104 is energized from ground at armature 114 but is slow to pull up so as to allow time for operating the line relay at the cord circuit O over the upper talking conductor as explained. On energizing, relay 104 disconnects ground from the conductor 130 and the initial energizing circuit of the line relay 206 of the cord circuit O. At armature 120 and its working contact, relay 104 connects ground to the release trunk conductor 77; at armature 121 and its working contact closes a circuit through the polarizing winding of the electropolarized relay 105; and at armature 118 and its working contact completes a bridge across the trunk conductors 130 and 131 which may be traced over the following path: conductor 130, armature 113 and its working contact, working contacts of armature 118 and said armature, armature 116 and its resting contact, lower winding of the electro-polarized relay 105, normally closed springs controlled by armature 108 of relay 100, right hand winding of the impedance coil 106, and working contact of armature 111 and said armature to conductor 131. By the closure of this bridge across the trunk line a circuit is completed for maintaining energized the double wound line relay 206 of the cord circuit O.

When the line and release relays of cord circuit O are operated, as above explained, the latter relay at armature 232 opens a point in the circuit of the supervisory lamp SL and at its working contact connects ground to conductor 257. At armature 233, relay 205 prepares a point in the impulsing circuit; at armature 235 and its working contact connects ground to the lower winding of the line relay 206 as previously explained.

It may well be mentioned at this point that the register selector C' is a preselecting switch, and it is assumed that the switch C' has preselected the register set shown in the drawings in Fig. 3. The method of preselecting an idle register set will be fully described hereinafter. When relay 205 pulls up it closes at armature 234 an energizing circuit for relay 204 as follows: from ground by way of armature 224 and its resting contact, lower winding of relay 204, working contact of armature 234 and said armature, armature 222 and its resting contact, resting contact of armature 218 and said armature, conductor

301, wiper 301', bank contact connected to terminal pin 305, jumper 308, terminal contact 311, conductor 372, armature 331 and its resting contact, terminal 379, jumper 380, terminal 381, armature 334 and its resting contact, and winding of relay 325 to battery.

When the above traced circuit for relay 325 is closed, said relay energizes and at armature 338 and its resting contact opens a normally closed short circuit from around the relay 323, at armature 339 and its working contact closes a circuit for operating the time switch P, and at armature 340 and its resting contact opens one of the several energizing circuits for the relay 392.

Returning now to the cord circuit O, relay 204 is energized over the previously traced circuit and at armature 227 and its working contact prepares a point in the circuit for the call lamp CL, at armature 228 and its working contact prepares a circuit for relay 201, at armature 230 and its working contact closes a locking circuit for itself through armatures 220 and 217 to grounded conductor 257, and at armature 231 and its working contact connects direct ground to the release trunk conductor 301 to guard the seized register set from being seized by other register selectors such as C'. At armature 229 and its resting contact, relay 204 opens a point in the circuit for the busy relay 202, so that when impulsing is started the busy relay will not be energized from ground at armature 236, and at its working contact prepares the impulsing circuit extending over conductor 303 to the register set.

Everything is now in readiness for the transmission of the second series of impulses. The subscriber will now operate his calling device in accordance with the digit 3, which will cause line relay 101 of the repeater E to fall back a corresponding number of times, which results in the operation of slow relay 103 for placing a direct bridge across the trunk conductors 130 and 131. The operation of line relay 101 causes the circuit of the line relay 206 to be interrupted a like number of times. Each time line relay 206 falls back an impulse is transmitted to stepping magnet 461 over the following circuit: ground, armature 236 and its resting contact, working contact of armature 233 and said armature, armature 229 and its working contact, impulse conductor 303, wiper 303', Fig. 3, bank contact engaged by wiper 303', terminal pin 306, jumper 309, terminal contact 312, conductor 371, winding of relay 327, wiper 355 of the register controlled switch RCS, conductor 360, stepping magnet 461 of the register switch R1 to battery. By the operation of the stepping magnet 461 wiper 464 of the register switch R1 is advanced three steps and is brought to rest in engagement with the third contact of its bank. The slow acting relay 327 is energized in series

with stepping magnet 461 and retains its armature 344 attracted while the said magnet is being operated. In operated position, relay 327 closes, a circuit for the slow acting relay 328, which is held in operated position also during the operation of the first register switch. After the last impulse has been transmitted, the slow-acting relay 327 will deenergize and break the circuit of relay 328 at armature 344. Since the latter relay is slow-acting, however, a circuit will be closed for an instant which extends from the grounded armature 344 by way of its resting contact, working contact of armature 345 and said armature, and the winding of stepping magnet 359 of the register control switch RCS to battery. One impulse is thus transmitted to the stepping magnet 359, and the wipers 355 and 356 are advanced one step into engagement with the second contacts in their respective banks. The advance of wiper 356 is of no effect, but when wiper 355 moves from its first contact to the second, the operating circuit is thus transferred to conductor 361 which extends to the stepping magnet 441 of the register switch R2.

It may well be mentioned at this time that relay 323 was energized as soon as the register switch R' moved off-normal. The circuit for relay 323 may be traced as follows: from ground through low resistance winding of relay 322, winding of high resistance relay 323, conductor 405, off-normal springs 463, winding of release magnet 462, to battery. The relay 322 and release magnet 462 are not energized in this circuit on account of the high resistance of relay 323. At armature 364, relay 323 removes ground from conductor 376 and prepares a circuit for relay 324 at its working contact. Relay 324 however does not energize at this time on account of the ground connection at armature 231, Fig. 2, extending over conductor 301.

The calling subscriber will now operate his calling device in accordance with the next digit in the desired number. As a result, the line relay 206 in the cord circuit operates the same as before, but now sends four impulses over the operating circuit to the stepping magnet 441 of the register switch R2. The stepping magnet 441 is thus operated to advance its wipers 444 four steps and the wiper is brought to rest in engagement with the fourth contact in its banks.

The slow acting relays 327 and 328 are energized during the transmission of the second series of impulses the same as during the first, and when the impulses cease another impulse of current is transmitted to the stepping magnet 359 of the register control switch RCS, thus advancing the wipers 355 and 356 another step, and transferring the operating circuit by way of conductor 362 to the stepping magnet 421 of the register switch R3.

It will not be necessary to consider in detail the manner in which the register switches R3 and R4 are operated. When the digit 5 is called a series of five impulses are transmitted to the stepping magnet 421 of the register switch R3 and the wiper 424 is advanced into engagement with the fifth contact in its bank. At the end of the series of impulses, the register controlled switch is operated one step and the operating circuit is transferred by way of conductor 363 to the stepping magnet 401 of the register switch R4. The series of six impulses which results from the calling of the final digit thus causes the operation of the stepping magnet 401 and the wiper 404 is advanced into engagement with the sixth contact in its bank. The stepping magnet 359 of the register control switch is given another impulse of current also at the end of the last series of impulses and wipers 355 and 356 are advanced one more step.

By the last operation of the register control switch RCS wiper 356 is brought into engagement with the fifth contact in its bank and ground is placed on conductor 369, resulting in the energization of relay 326. Upon attracting its armature 342, relay 326 stops the operation of the timing switch P, while at armature 343 ground is connected by way of armature 330 for lighting the set-up lamp 370 thereby indicating to an operator that a call has been set up on the third register set. Relay 326 at armature 343 and its resting contact removes a short circuit from around the relay 329 and at its working contact closes a circuit over the conductor 377 for energizing the relay 281 of the switch CCS in Fig. 2. Armature 343 also removes ground from conductor 376 thereby removing ground from the bank contact in the switch CCS which corresponds to the register set shown in Fig. 3.

The consecution switch CCS has all its bank contacts normally grounded over conductors such as conductor 376 and as soon as relays such as relays 326 and 323 are energized ground is removed from the bank contact corresponding to the register set in use.

Responsive to the energization of relay 281 over the above traced circuit, said relay at armature 282 and its working contact closes a circuit for operating the stepping magnet 283 by way of the grounded bank contacts of the consecution switch CCS. The stepping magnet 283 energizes from ground on the grounded bank contacts encountered by wiper 280, interrupts its own circuit, and continues to operate in a buzzerlike manner until the wiper 280 encounters the bank contact connected to conductor 376 from which ground has been previously removed. Responsive to the wiper 280 coming into engagement with the bank contact connected to conductor 376, a circuit is no longer closed for

the stepping magnet and a circuit may now be traced for energizing the high resistance relay 329 Fig. 3, as follows: from ground winding of relay 329, armature 332 and its resting contact, conductor 378, conductor 376, bank contact individual to the register set shown in Fig. 3, wiper 280, working contact of armature 282 and said armature, interrupter springs of the stepping magnet 283, and winding of stepping magnet 283 to battery. Due to the high resistance of relay 329 the stepping magnet 283 is not energized over the above traced circuit. Relay 329, however, is energized and at armature 353 connects ground to conductor 373 for lighting the call lamp CL over a circuit as follows: from ground, working contact of armature 353 and said armature, conductor 373, terminal 313, jumper 310, terminal 307, bank contact of the register selector C', wiper 304', conductor 304, armature 227 and its working contact, winding of relay 211, resting contact of armature 219 and said armature, armature 244 and its resting contact, call lamp CL to battery. Relay 211 is energized over the above traced circuit and at armature 248 disconnects the supervisory lamp SL. Other calls may be registered on the other register sets at any time now and when the registration is completed the set-up-pilot lamps, such as lamp 370, corresponding to the register sets in use will be lighted, but this has no effect on the consecution switch CCS, which makes no further movement until the call on the third register set has been disposed of.

Relay 329 is the relay which switches over the registered call to the lamps of the indicating device and the manner in which this is done will now be pointed out, it being recollected that the wipers 464, 444, 424 and 404, are now resting on the 3rd, 4th, 5th, and 6th contacts in their respective banks. When the armatures 348 of relay 329 are operated, ground is connected to conductors 349 to 352, inclusive. It follows, therefore, that with the conductors 349 to 352, inclusive, grounded the conductors 476, 455, 343, and 413 will also be grounded. These latter mentioned conductors extend to the indicating device V and terminate in the #3 lamp of the first group, the #4 lamp of the second group, the #5 lamp at the third group, and the #6 lamp in the fourth group, respectively. The other side of the lamp is connected to battery and the lamps mentioned are accordingly illuminated.

The manner in which the operator handles the call thus displayed before her will now be considered. When the relay 329 in Fig. 3 pulls up and closes the circuit for displaying the registered number to the operator, it also closes at its armature 353 the circuit for the call lamp CL in the cord circuit O. The lighting of the lamp CL which is individual to the cord circuit O is lighted simultaneously with the lamps in the indicating device V, thus enabling the operator to know which one of the cord circuits is being used by the automatic subscriber, whose wanted number is at this particular time being shown on the indicating device. Having observed the #3456 and knowing by the lighting of the called lamp CL that the cord circuit O is the one in use, the operator will test the multiple jack of the line 3456 with the tip of her plug in the usual manner in order to find out whether or not the line is busy. If the line is found to be in use, the operator will hear the well known busy click, and will immediately operate her busy key BK. The two keys indicated by BK are in reality one key and have been shown as two keys so as to simplify the drawings. By the operation of the upper busy key BK the stepping magnet 283 of the consecution control switch CCC is energized. A circuit is also closed through the lower busy key BK from ground at said key, through working contact of armature 242 of relay 209 which was previously energized in parallel with relay 211, armature 242 and its resting contact, winding of relay 202 to battery. Relay 202 at armature 220 opens the locking circuit of relay 204 which thereupon deenergizes, at armature 222 removes ground from the release trunk conductor 301, and at armature 223 and its working contact connects the busy tone through the condenser 259, through the lower right hand winding of relay 208 to battery. The busy tone is now transmitted to the calling subscriber in the well known manner and need not be explained in detail.

By the removal of ground from the release trunk conductor 301, the short circuit around relay 324 has been removed, and said relay energizes over a circuit from ground at armature 364 in series with relay 325. Relay 324 upon energizing closes at armature 336 and its working contact a circuit for releasing the register control switch, the time switch T, and all of the register switches R1 to R4 inclusive, as follows: ground through the low resistance winding of relay 322, armature 336 and its working contact, off normal springs 357 of the register control switch RCS, release magnet 358 to battery; to the resting contact of armature 347 and said armature, off normal springs 367 of the time switch P, release magnet 366 to battery; to conductor 405 from which point ground is connected to the release magnets 402, 422, 442 and 462 through off-normal contacts 403, 423, 443 and 463, respectively. The register control switch RCS, the time switch P, and the register switches R1 to R4, inclusive, release in the well known manner. Relay 322 is energized in series with the various release magnets and at armature 334 and its working contact connects ground to the conductor 372 thereby rendering the register set 130

busy until the apparatus in the set has been completely restored to normal. When relay 324 operates its armature 336, relay 323 is short circuited and after an interval, said relay deenergizes. Relay 323 upon deenergizing opens at armature 364 the circuit of relays 324 and 325 which thereupon deenergize. At armature 364 and its resting contact, relay 323 connects ground to conductor 376 so as to busy the register set in the consecution control switch. Relay 325 deenergizes before relay 324 thereby maintaining at armature 338 the short circuit around relay 323. As soon as all of the register switches, the 15 register control switch and the time switch P have been returned to normal, the circuit of relay 322 is opened at the various off normal contacts. In case any one of the above switches did not properly release, relay 322 20 would be maintained energized, thereby maintaining the register set busy. The relay 326 was also deenergized responsive to the release of the register control switch thereby causing relay 281 of the switch CCS to deenergize. Relay 329 is again short circuited and said relay releases and disconnects ground from conductors 349 to 352, inclusive. All of the apparatus shown in Figs. 3 and 4, 25 have been returned to their normal positions, and are available for use in another call.

When the operator releases the busy key BK, the stepping magnet 283 of the consecution control switch CCS deenergizes and advances the wiper 280 one step.

35 The reason for holding stepping magnet 283 energized during the time the busy key is depressed is to prevent the operation of the switch CCS thereby preventing the operation of busy relays in other cord circuits when 40 calls on the other cord circuits are waiting to be displayed.

Assuming however, that the line is found to be idle, the operator will at once insert the plug P into the jack of the wanted line, which 45 in the present case is the jack J. As soon as the plug is inserted into the jack, a circuit is completed for the sleeve relay 210 in series with the cut-off relay 261 of the called line, and the latter relay is energized to clear the 50 line of its normal battery and ground connections in the usual manner. Relay 210 is energized also and at armature 240 prepares a circuit for the supervisory lamp SL, at armature 241 opens the circuit of relay 209 55 at its resting contact and at its working contact closes a circuit for energizing relay 201, at armature 243 and its resting contact opens the circuit of the busy relay 202, at armature 244 and its resting contact opens the circuit of the call lamp CL, at armature 245 60 and its working contact connects ground to conductor 279, at armatures 246 and 247 and their working contacts completes a ring back circuit for transmitting ringing induction to the calling subscriber, at armature 65

ture 247 and its working contact connects generator to the called line, and at the resting contact of armature 247 disconnects the operator's headset. Ringing current is now connected to the called subscriber over the following path: from generator GEN, winding of relay 212, resting contact of armature 256 and said armature, working contact of armature 247 and said armature, tip of plug P, tip of jack J through the called subscriber's ringers, back over the ring conductor of plug P, armature 250 and its resting contact, resistance 259, to battery.

When the sleeve relay was energized it closed a circuit for energizing relay 201 as follows: grounded conductor 304, armature 227 and its working contact, armature 241 and its working contact, working contact of armature 228 and said armature, normally closed springs controlled by armature 217, 85 and winding of relay 201 to battery. Relay 201, upon energizing, closes a locking circuit for itself at armature 217 and its working contact and at armature 217 and its resting contact opens the locking circuit of relay 204. At armature 218, relay 201 disconnects ground from the release trunk conductor 301, and at armature 219 prepares a substitute circuit for the call lamp CL which includes the interrupter I for flashing the call lamp CL 95 in case the operator removes the plug P from the jack prematurely.

Responsive to the removal of ground from the conductor 301 the short circuit around relay 324 is removed and said relay energizes in series with relay 325. The operation of the relay 322 and the release magnets of the various switches in Figs. 3 and 4 are now the same as previously described and the apparatus is restored to normal. The register control switch, the register switches, and the consecution control switch are now in readiness to be used for another call.

Referring now to the cord circuit O, it has been explained how the connection has been completed to the line of the called station A', and how ringing current is projected over the called line to signal the subscriber. During the ringing operation a tone is induced in the lower right hand winding of the repeating coil of the cord circuit O by means of which the calling subscriber is advised that the called subscriber is being signalled. When the called subscriber answers, the ring cut-off relay 212 energizes in a well known manner and closes a circuit at armature 249 for relay 213 from ground over the sleeve of plug P and jack J. Relay 213, upon energizing, at armature 251 completes a locking circuit for itself and at armatures 250 and 256 and their resting contacts disconnects the generator from the called line and at their working contacts connects the line of the called subscriber to the right hand windings of the repeating coil thereby com-

pleting a talking circuit for the called subscriber which includes the lower and upper windings of relay 208 and the right hand windings of the repeating coil. Relay 208 is energized over the called subscriber's loop and at armature 239 completes an energizing circuit for the reversing relay 207. In energized position, relay 207 reverses the trunk conductors 130 and 131 as regards their connections with the windings of the line relay 206, and the direction of current flow in the trunk line is thus reversed. Due to the reversal of current flow in the trunk line the polarized relay 105 in the repeater E is now energized and at armature 119 and its working contact completes a circuit for energizing the reversing relay 100 of the repeater E. Upon energizing relay 100 reverses the trunk conductor 76 and 78 as regards their connections with the winding of the line relay 101, and the direction of current flow in the calling line is thus reversed. This operation may be used for operating a meter or for similar purposes, and is provided in accordance with standard practice, although it is of no utility in the particular system shown herein.

The required connection having been established, the subscribers may now converse as desired. When the conversation is finished both subscribers will hang up their receivers, and the replacement of the receiver at the calling station A causes the deenergization of the line relay 101 in the repeater E and also the release of slow acting release relay 102. Relay 101 upon releasing, completes a circuit for relay 103 so that when relay 102 deenergizes, ground is removed from release conductor 77 thereby allowing the automatic switches to be restored to normal in the usual manner. The bridge across the trunk conductors 130 and 131 being broken by the deenergization of line relay 101 of the repeater E the circuit of the line relay 206 in the cord circuit O is thereby opened whereupon said relay deenergizes. After a short interval of time the slow acting relay 205 also deenergizes and closes a circuit for the supervisory lamp SL at armature 232, and at the same armature also opens the circuit of relays 207 and 201 which thereupon deenergize. Relay 205 also removes ground from conductor 279 and prepares a circuit for relay 203. When the slow-acting relay 102 of the repeater E deenergizes it opens at armature 114 a circuit for relay 104 and at the same armature by way of its resting contact substitutes another circuit for energizing relay 104 as follows: from ground by way of armature 245 and its working contact, conductor 279, lower winding of line relay 206, normally closed springs controlled by armature 238, lower left hand winding of the repeating coil, resting contact of armature 216 and said armature, conductor 131, resting

contact of armature 114, and winding of relay 104 to battery. Relay 104 energizes over the above traced circuit but due to its high resistance, the line relay 206 is not energized. At armature 120, relay 104 connects ground to the release conductor 77 thereby maintaining this trunk circuit busy to the automatic switches in the automatic office as long as the plug P remains inserted in the jack J.

The automatic switches now have been released, a disconnect signal has been given to the operator, and the trunk line in use has been made busy pending the pulling down of the connection. When the operator observes the lighted supervisory lamp SL she will remove the plug of the cord circuit O from the jack and relays 210 and 213 are deenergized and restored to normal. By the falling back of relay 210 the circuit of the supervisory lamp SL is broken at armature 240 and at armature 245 ground is removed from conductor 279 thereby permitting the relay 104 of the repeater E to deenergize and remove ground from the release trunk conductor 77. All the apparatus has now been restored and is ready for use in handling another call.

Certain details of the system will now be explained which it was not convenient to go into before, and the first thing which will be considered is the preselecting operation of the register selector C'. For this purpose, it will be assumed that the cord circuit O is idle, that the wipers of the register selector switch C' are standing in the position shown in the drawing, Fig. 3, and that the register set associated with these bank contacts becomes busy. Under the above conditions a circuit can now be traced to the lower winding of the differential relay 203 of the cord circuit O over the following path: from ground on the bank contact associated with the busy register set, wiper 301', conductor 301, armature 218 and its resting contact, resting contact of armature 222 and said armature, armature 234 and its resting contact, and lower winding of relay 203 to battery. Relay 203 energizes over the above traced circuit and at armature 225 maintains the above traced circuit independent of armature 234 so that if the cord circuit should be taken into use, the circuit of the relay 203 would not be opened by the operation of the release relay 205. At armature 224 and its resting contact, relay 203 opens the energizing circuit for relay 204 so that relay 204 cannot energize until after an idle register set has been selected. In addition to the above, relay 203 at armature 224 and its working contact connects ground to conductor 302 thereby closing a circuit for the stepping magnet 320 of the register selector C' so that said stepping magnet will operate in a manner of a buzzer until ground is removed from conductor 302. Although relay

203 is a differential relay the resistance inserted in series with the upper winding will not permit the relay to be deenergized when armature 224 connects ground to the upper winding of said relay. As long as the wiper 301' encounters grounded contacts of busy register sets, relay 203 will be maintained energized through its lower winding. It will now be assumed that an idle register set is reached and when the test wiper 301' engages the bank contact associated therewith, said contact will not be grounded, but will have a battery potential thereon. Under this condition the circuit to the lower winding of relay 203 is opened. Due to the current flow through the upper winding of relay 203, magnetic flux will be built up in opposition to the magnetic flux created by the circuit through the lower winding and when the flux reaches a certain point said relay is quickly deenergized, thereby removing ground from conductor 302 and stopping the operation of the register selector on the idle register set.

Having described the operation of the system as a whole, a detailed description will now be given of the main feature of this invention which relates to the method of multiplying the register sets, which are only eight in number to the register selector banks. The multiplying of the register sets in the banks of the register selectors is accomplished by the aid of an intermediate distributing frame. The banks of all the register selectors at the position are connected in multiple and a cable connects the multiply connected banks with one side of the distributing frame, where the cable is terminated on twenty-five sets of terminal pins.

In the bottom half of Fig. 4, the distributing frame is indicated by the reference characters I. D. F. The lower row of twenty-five terminals are the terminals for the release trunk conductors coming from the bank contacts of the register selectors. The release trunk conductors of the eight register sets are connected to eight terminal contacts on the other side of the I. D. F. Although only the release trunk terminals are shown, it will be understood that there are three terminals to each set. As the register selectors have access to only eight register sets the terminal pins are divided into three groups, the first group comprising terminal pins 1 to 8, inclusive, the second group 9 to 16, inclusive, and the third group 17 to 25, inclusive. The eight register sets are cross connected by jumpers at the I. D. F., to the terminal pins numbered 1 to 25, inclusive. The number 1 register set is multiplied to the #1, #13, and #19 terminal pins, the number 2 register set is multiplied to the #2, #9, and #22 terminal pins, the number 3 register set is multiplied to the #3, #14, and #17 terminal pins, the number 4 regis-

ter set is multiplied to the #4, #10, and #20 terminal pins, the number 5 register set is multiplied to the #5, #15, and #23 terminal pins, the #6 register set is multiplied to the #6, #11, and #18 terminal pins, the number 7 register set is multiplied to the #7 and #21 terminal pins, and the number 8 register is multiplied to the #12 and #24 terminal pins. The eighth, sixteenth, and twenty-fifth terminal pins are dead and are cross connected in such a manner that they provide stopping positions for the register selectors in case all eight register sets become busy. With the register sets multiplied at the I. D. F., in the manner pointed out it necessarily follows that each of the register sets is accessible to a register selector at a plurality of points in its bank. Although the corresponding bank contacts of all the register selectors at the position are connected in a straight multiple, the cross connections at the I. D. F., divides each bank into a plurality of groups of bank contacts and provides a slip between the bank contacts in each of the groups. Considerable saving is effected by multiplying the register sets at the I. D. F., because it permits changes such as varying the number of register sets to be used or for varying the slip in the multiple between bank contacts to be readily and easily made at the same time keeping the multiples straight between banks.

The slip in the register selector bank contacts between groups is provided for the purpose of preventing all the idle preselecting register selectors from preselecting the same idle register set on their next operation in case they had previously selected the same register set. For example, it will be assumed that there is a register selector in engagement with the multiples of the first register set of the different groups that is, a first register selector is in engagement with the #1 bank contact in the first group of its associated bank, a second register selector is in engagement with the #13 bank contact in the second group of its associated bank, and a third register selector is in engagement with the #19 bank contact in the third group of its associated bank. Assuming now that the #1 register set becomes busy, ground is connected to the multiples of said set causing all of the register selectors which are in engagement therewith to start hunting to preselect another idle register set. The said first register selector will step one step into engagement with the 2nd bank contact or the multiples of the #2 register set, the said second register selector will step one step into engagement with the 14th bank contact or the multiples of the #3 register set, and the said third selector will step one step into engagement with the 20th bank contact or the multiples of the #4 register set. It can be seen from the foregoing that each register selector, which have their

wipers positioned in different groups, selects a different register set for each corresponding step when they are initially started from multiples of the same register set.

Having explained in detail how the bank contacts of the register selectors are connected in a slip multiple by means of jumpers at the I. D. F., when eight register sets are to be used, I will now briefly point out how the bank contacts of the register selectors are cross-connected to the register sets at the I. D. F., when a variable number of register sets is to be used at an operator's position.

The following is a chart showing the slip multiple arrangement for cross-connecting the bank contacts of the register selectors at the I. D. F., to the register sets:

Chart

Register sel. bank contact	8 Reg. sets	7 Reg. sets	6 Reg. sets	5 Reg. sets
1	1	1		
2	2	2	1	1
3	3	3	2	2
4	4	4	3	3
5	5	5	4	4
6	Dead	6	5	Dead
7	7	7	2	2
8	#1 dead	2	4	4
9	2	2	6	1
10	4	4	1	Dead
11	6	6	3	
12	8	Dead	3	3
13	1	1	Dead	5
14	3	3	5	1
15	5	5	1	4
16	#2 dead	7	6	Dead
17	3	3	3	2
18	6	6	2	5
19	1	Dead	Dead	4
20	4	1	4	3
21	7	4	1	Dead
22	2	7	5	1
23	5	2	2	5
24	8	5	6	3
25	#3 dead	Dead	3	2

Reading from left to right, the left hand column indicates the numbers of the register selector bank contacts which are connected to correspondingly numbered terminal pins on the I. D. F., and the other columns indicate the number of the register sets which are multiplied to the selector bank contacts in the following manner. In order to explain the chart it will be assumed that only six register sets are to be used at an operator's position and therefore only the first and fourth columns may be considered. The #1 bank contact is multiplied to the #1 register, the #2 bank contact to the #2 register set, the #3 bank contact to the #3 register set, the #4 bank contact to #4 register set, the #5 bank contact to the #5 register set, and the #6 bank contact is connected to a dead terminal pin. In the next group of bank contacts the #7 bank contact is multiplied to the #2 register set, the #8 bank contact to the #4 register set, the #9 bank contact to the #6 register set, etc. In case 5 or 7 register sets were to be used at an operator's position, the register sets would be cross-connected at the I. D. F., in an obvious manner. It can

plainly be seen from the foregoing that in order to change the number of register sets to be used or in order to change the slip multiple it is only necessary to change the cross connections or jumpers at the I. D. F. ⁷⁰

It can plainly be seen that this method of multiplying is not necessarily limited to the register sets shown in the drawings and is readily adaptable for use with other switches. ⁷⁵

There are provided in the instant case eight register sets per operator's position, seven of which are normally available for use while the eighth is artificially made busy. When all seven register sets become busy, a circuit will be completed for energizing the all trunk busy relay ATB to busy the operator's position. A still further feature of the invention which may be described in conjunction with the preceding, relates to the means for rendering the eighth register set idle so that if a call should come into the operator's position before said position has been made busy, the call would seize the eighth register set and the connection would be completed in the same manner as previously described. ⁸⁵

Referring now to Fig. 3, the first seven register sets have their terminals 379 and 381 connected by a jumper 380 and have their armatures 340 connected by a conductor such as 386 to terminal 387. All of the terminals 387 are connected to a common conductor which extends to the relay 392. The eighth register set, or the register set normally held in reserve, is connected in the following manner: the jumper, such as jumper 380, is cut and the terminal 379 is connected to terminal 383 and the terminal 381 is connected to the terminal 382. At armature 340 the conductor such as conductors 386 is moved from terminal 387 to terminal 388 which in turn is connected to an individual conductor 390 for controlling the relay 391. ¹⁰⁰

It will now be assumed that the first seven registers are busy and under such conditions ground at the various seven register sets have been disconnected from the common conductor 389, thereby permitting relay 392 to deenergize. Relay 392, upon deenergizing, removes ground from armature 396 thereby rendering the eighth register set selectable. At armature 397 and its resting contact, relay 392 prepares a circuit for relay 393. At armature 398 and its resting contact, relay 392 connects ground to conductor 399 for energizing the all trunk busy relay ATB Fig. 2. Relay ATB, upon energizing, connects ground to the lower winding of all line relays such as 206 at the operator's position. The ground connections to the lower winding of the line relays extend over the conductors 131 causing the energization of the relays 104 as previously explained. The latter relays, upon energizing, connect ground potentials to armatures 120 thereby rendering the out- ¹⁰⁵ ¹¹⁰ ¹¹⁵ ¹²⁰ ¹²⁵ ¹³⁰

going trunks extending to the operator's position busy.

It will now be assumed that a call has come in during the interval in which the last of the seven register sets was seized and the trunks extending to the operator's position were made busy. Under this conduction such a call would operate the register selector such as C' to seize the eighth register set. The call would then be completed in the same manner as previously described. However, as soon as the eighth register set is seized, the circuit for relay 391 will be opened due to the removal of ground from conductor 390 whereupon said relay will deenergize and close a circuit for operating relay 393. At armature 394 relay 391 closes a shunt around the armature 396 so that if one of the first seven register sets becomes idle the operation of relay 392 will not interfere in any way with the call being set up on the eighth register set. When relay 393 is energized over the above traced circuit said relay removes ground from conductors 406 and the dead contacts in the terminal block on the I. D. F., Fig. 4, thereby providing a plurality of stopping positions for the idle register selectors when all eight register sets are busy. As soon as one register set becomes idle the circuit of relay 393 is broken and ground is again applied to the dead contacts.

Having described my invention, what I consider to be new and desire to have protected by Letters Patent will be pointed out in the appended claims:

What I claim is:

1. In a telephone system, a group of automatic switches each having a plurality of bank contacts, multiple connections between corresponding bank contacts of said switches, an intermediate distributing frame, a terminal block on said frame having terminal pins corresponding in number to the number of bank contacts in each of said switches, conductors extending from each one of said multiple connections to a corresponding terminal pin, said terminal pins divided in a plurality of groups, a group of register sets, said register sets being less in number than the number of said terminal pins and terminating on said frame in terminal contacts, a jumper for connecting each one of said terminal contacts to one of said terminal pins, and other multiple connections extending between terminal pins of different groups by means of which said register sets are multiply connected in an irregular manner to the terminal pins in different groups.

2. In a telephone system, a group of line switches having corresponding bank contacts connected in multiple, and means including an intermediate distributing frame for dividing the bank contacts of said switches into a plurality of groups and for introducing

a slip multiple between bank contacts of said groups.

3. In a telephone system, a group of line switches having corresponding bank contacts connected in multiple, a group of trunks less in number than the number of bank contacts in each of said switches, and means including an intermediate distributing frame whereby the bank contacts of each switch are divided into a plurality of groups and whereby said trunk lines are connected to said bank contact groups in slip multiple connections.

4. In a telephone system, a group of line switches having corresponding bank contacts connected in multiple, a group of trunks less in number than the number of bank contacts in each of said switches, and means including an intermediate distributing frame for dividing the bank contacts of said switches into a plurality of groups and for cross-connecting said trunk lines to said bank contact groups in slip multiple connections.

5. In a telephone system, a group of switches having corresponding bank contacts connected in multiple, and means for dividing the bank contacts of said switches into a plurality of groups and for producing a slip multiple between bank contacts of said groups.

6. In a telephone system, a group of switches having corresponding bank contacts connected in multiple, means for dividing the bank contacts of said switches into a plurality of groups, a group of trunk lines less in number than the number of bank contacts in each of said switches, and means whereby the corresponding bank contacts in each group are connected to a different one of said trunk lines.

7. In a telephone system, a group of switches having corresponding bank contacts connected in multiple, means for dividing the bank contacts of said switches into a plurality of equal groups, trunk lines terminating in the bank contacts of one of said groups, and multiple connections between said groups such that the order of access to the said trunk lines from each of said bank contact groups is different.

8. In a telephone system, a group of pre-selecting rotary line switches having corresponding bank contacts connected in multiple, and means including an intermediate distributing frame for dividing the bank contacts of said switches into a plurality of groups and for introducing a slip multiple between bank contacts of said groups to eliminate the tendency of a number of switches to line up on the same trunk.

9. In a telephone system, a group of pre-selecting rotary line switches having corresponding bank contacts connected in multiple, means for dividing the bank contacts of said switches into a plurality of groups,

trunk lines terminating in the bank contacts of one of said groups, and multiple connections between said groups for introducing a slip multiple between bank contacts of said groups to eliminate the tendency of a number of switches to line up on the same idle trunk line when the switches are operated from a multiple of the same trunk line.

10. In a telephone system, a group of pre-selecting rotary line switches having corresponding bank contacts connected in multiple, an intermediate distributing frame for dividing the bank contacts of said switches into a plurality of groups, a plurality of trunk lines less than the number of bank contacts in each of said switches terminating in said intermediate distributing frame in one of said groups, and multiple connections between non-corresponding contacts in said groups at said intermediate distributing frame to reduce the tendency of said switches from simultaneously preselecting the same trunk line when the switches are stepped from a multiple of the same trunk line.

25. 11. In combination, a plurality of multi-contact switch banks each comprising groups of contacts, multiple connections between corresponding contacts of the different switch banks, and slip multiple connections between the contacts of the different groups of contacts.

30. 12. In combination, a plurality of multi-contact switch banks each comprising groups of contacts, multiple connections between corresponding contacts of the different switch banks, and a cross-connecting rack for multiply connecting non-corresponding contacts of the groups.

35. 13. In combination, a plurality of switch banks each comprising groups of contact sets, multiple connections between corresponding contact sets of said banks, multiple connections between non-corresponding contact sets of the different groups, and connections from the individual contact sets comprising one of said groups to switching devices.

40. 14. In combination, a plurality of switch banks each comprising groups of contact sets, multiple connections between corresponding contact sets of said banks, multiple connections between non-corresponding contact sets of the different groups, connections from the individual contact sets comprising one of said groups to switching devices, and a cross-connecting rack for effecting said last two connections.

45. 15. In combination, a single level switch bank comprising a plurality of groups of contact sets, a cross-connecting rack, and means including said rack for inter-connecting contact sets of the various groups so that the order of access to connected contact sets is different for each group.

50. 16. In combination, a single level switch bank comprising a plurality of groups of

contact sets, registering devices connected to the contact sets of one group, and a cross-connecting rack for inter-connecting the contact sets of the various groups so that the order of access to said registering devices is different for each group.

5. 17. In combination, a group of switches having corresponding bank contacts connected in multiple, means for dividing the bank contacts of said switches into a plurality of groups, registering devices connected to the bank contacts of one of said groups, and multiple connections between contacts of said groups such that the order of access to said registering devices from each of said contact groups is different.

In witness whereof, I hereunto subscribe my name this 4th day of December, A. D. 1928.

RUDOLPH F. STEHLIK.
